McGARVEY E. TATE

DOORCHECK

Filed March 28, 1923

INVENTOR.

M.E. Tate

BY
Watson E. Coburn
ATTORNEY.

Patented Oct. 7, 1924.

UNITED STATES PATENT OFFICE.

MCGARVEY E. TATE, OF SOMERSET, KENTUCKY.

DOORCHECK.

Application filed March 28, 1923. Serial No. 628,303.

To all whom it may concern:

Be it known that I, MCGARVEY E. TATE, a citizen of the United States, residing at 5 Somerset, in the county of Pulaski and State of Kentucky, have invented certain new and useful Improvements in Doorchecks, of which the following is a specification, reference being had to the accompanying drawings.

10 This invention relates to door checks, and particularly to those checks which are mounted for swinging movement upon the door jamb and with which the door contacts as it closes.

15 The general object of this invention is to provide a door check of this character comprising two bumpers depending freely from a bracket supported by the door jamb and normally in the path of movement of 20 the door, these bumpers being so connected that if the door closes slowly the door will strike one of the bumpers and both bumpers will be swung gradually out of the way of the door to permit the door to close quietly, 25 and if the door is forcibly closed the door will strike one of the bumpers, which will be forced out of the way, but the other bumper will remain in the path of movement of the door to still further check it.

30 A further object of the invention is to provide a device of this character which is very simply and cheaply constructed, which may be applied readily, and which has been found to be thoroughly effective in use.

35 Another object is to provide a construction of this character which will permit the door to be closed slowly or forcibly closed quietly without slamming.

Other objects will appear in the course 40 of the following description.

My invention is illustrated in the accompanying drawings, wherein:—

Figure 1 is a fragmentary elevation of a door and door jamb showing my door 45 check device thereon and in dotted lines the position taken by the check when the door is swung to gently;

Figure 2 is a side elevation of the construction shown in Figure 1;

50 Figure 3 is a like view to Figure 1, but showing the position taken by the parts when the door is swung to rapidly or with force;

Figure 4 is a perspective view of the 55 bracket 10.

Referring to these drawings, A designates

the door jamb upon which the check is mounted and B the door coacting with the jamb. My device includes a bracket illustrated as formed of a single piece of wire. 60 This bracket is formed to provide a vertical open loop 10 which is adapted to lie flat against the outer face of the door jamb, the arms of which loop are bent into a more or less horizontal plane, one of the arms 12 65 extending straight outward from the door jamb, the other arm 11 extending outward and then being bent over the end of the arm 12. A screw 13 passes through the loop 10 and holds the bracket in position. 70

Swingingly mounted upon the arm 12 is a link 14. The upper end of this link is formed to provide a coil 15 which surrounds the arm 12 and swings thereon in a plane parallel to the face of the jamb. The length 75 of wire which forms the link 14 is extended straight downward from the coil 15 for a suitable distance as, for instance, two inches and is then bent forward and upward to form an eye 16. The wire is then bent forward and downward, as at 17, and then upward, as at 18, to form a support for a ball 19 which is preferably of rubber and preferably solid, this rubber ball constituting a bumper or buffer. 80

Swingingly connected to the first link 14 is a second link 20. This link is formed of a piece of wire bent to provide an elongated loop 21 which engages through the loop 16. The wire then extends downwardly 90 and laterally in a curve and then upwardly and laterally, as at 22, this straight portion 22 supporting the relatively larger ball 23, which is also preferably of rubber and preferably solid. This ball 23 is relatively 95

larger than the ball 19 but, as will be seen from Figure 2, the ball 19 is supported in advance of the ball 23, though the ball 23 extends laterally into the path of the door a slightly greater distance than the ball 19. 100 It will be noted that the link 20 swings laterally upon the eye 16 and also swings at right angles to the plane of movement of the link 14. This is necessary because the bumper 23 is normally disposed in front 105 of the junction between the door and the door jamb and if this link 20 did not swing outward the door would have difficulty in opening or the door would have to swing the bumper 23 laterally. With this construction, however, the door can swing the bumper 23 outward and in doing so will 110

also crowd it laterally so that there is no impediment to the free opening of the door

In the use of this device, the bracket is attached to the door jamb A by means of the screw 13, in such position that the bearing formed by the coil 15 is disposed just inside the edge of the jamb. Under ordinary circumstances the link 14 hangs straight downward and the ball or bumper 19 will project slightly into the path of movement of the door B and the ball 23 will also project into the path of movement of the door. If the door swings slowly toward its closed position, the free edge of the door will first strike the ball or bumper 19 and will act to swing the bumper to the left in Figure 1. If the door closes gently, the ball 19 will swing gently to the left in Figure 1 and the link 20 will swing with the link 14 so as to get the ball 23 out of the path of movement of the door and the door will simply be checked by the bumper 19. If, however, the door is slammed to or closes rapidly under the action of a spring, the door will first strike the ball 19 and swing this ball suddenly to the left, as in Figure 3. The greater weight of the ball 23, however, will prevent this ball from swinging as rapidly to the left as the ball 19 and the inertia of the ball 23 will hold it in the path of movement of the door so that the door will first strike the ball 19 and swing this ball out of the way and will then strike the ball 23, which will check the door. The door will slightly rebound and then swing to again and crowd the ball 23 to the left and the door will close quietly.

It will be seen that when the door swings to rapidly the joint between the links 14 and 20 will permit the upper ball 19 to move without disturbing the position of the lower ball. The lower ball then acts as a check or bumper to the door but as the door rebounds and then moves again toward the door jamb it slowly pushes or crowds the ball 23 laterally and the door is closed. If this rebound of the door is sufficient in amplitude to permit the ball 19 to swing back into place then, of course, when the door again moves toward its closed position after the rebound it pushes against the upper ball and pushes this ball slowly to one side and this slow action swings the lower ball out from the path of the door, permitting the door to close noiselessly.

It will be noted that the lower bumper 23 is formed with a corrugated or roughened face so as to afford a roughened surface with which the door has frictional engagement in closing. It will also be noted that the second named link has swinging movement not only parallel to the face of the door jamb but at right angles thereto.

It will be seen that this construction is very simple, that it may be very cheaply made, that it may be readily assembled, and

that if either of the balls become worn and do not operate properly other balls may be readily put in place, and that if either of the links should become bent or broken other links may be readily substituted. The parts are easily adjusted and after once being adjusted the check requires no attention. Furthermore, this check can be used either on right hand swinging doors or left hand swinging doors by simply reversing the link 20. It is obvious that slight changes might be made in the form of the parts and their arrangement without departing from the spirit of the invention as defined in the appended claims.

I claim:—

1. A door check comprising a bracket attachable to a door jamb, a link pivotally carried by the bracket for oscillation parallel to the plane of the front face of the door jamb and depending from the bracket, a bumper carried by the link, a second link swingingly engaged with the first named link and oscillatable with the first named link or independently thereof in the same plane or in a plane at right angles to the first named link, and a bumper carried by the second named link and disposed in the same vertical plane thereto but in advance of the plane of the second named bumper.

2. A door check comprising a bracket attachable to a door jamb, a link pivotally carried by the bracket for oscillation parallel to the plane of the front face of the jamb and depending from the bracket, a globular elastic bumper carried by the link, a second link swingingly engaged with the first named link and oscillatable with the first named link or independently thereof in a plane parallel to the front face of the door jamb or in a plane at right angles thereto, and a globular elastic bumper carried by the second named link and larger than the first named bumper, the first named bumper being disposed in the same vertical plane but in advance of the second named bumper.

3. A door check comprising a bracket attachable to a door jamb, a wire link formed to provide an eye engaging the bracket, the link normally extending straight downward toward said eye, then being bent forward and rearward to form an eye and then forward and upward, a globular, elastic buffer mounted upon said last named upwardly extending portion, a second named link formed at its upper end to provide an eye engageable with the second named eye of the first named link, the second named link below this eye extending downwardly and laterally and then upwardly in a direction toward the edge of the door jamb, and an elastic, globular bumper mounted upon this last named upwardly extending portion, the last named bumper being disposed in a plane inward of the first named bumper.

4. A door check comprising a bracket attachable to a door jamb, a wire link formed to provide an eye engaging the bracket, the link normally extending straight downward toward said eye, then being bent forward and rearward to form an eye and then forward and upward, a globular elastic buffer mounted upon said last named upwardly extending portion, a second named link formed at its upper end to provide an eye engageable with the second named eye of the first named link, the second named link below this eye extending downwardly and laterally and then upwardly in a direction toward the edge of the door jamb, and an elastic, globular bumper mounted upon this last named upwardly extending portion, the last named bumper being disposed in a plane inward of the first named bumper, the last named buffer being formed to provide a roughened surface with which the door is adapted to frictionally engage.
5. A door check comprising a bracket formed of a single piece of wire and attachable to a door jamb, the bracket being formed to provide an eye, arms extending at right angles to the eye, a link having a straight portion and a coil at the upper end of the straight portion surrounding one of said arms and pivotally engaged therewith, the link at its lower end being bent to form an eye, then extended upward and outward

and then upward, a globular, elastic bumper mounted upon this upward extension, and a second link formed at its upper end to provide a loop engageable with said eye, the link extending downwardly and laterally below said loop and then extended upwardly and laterally in an opposite direction, and a globular, elastic bumper mounted upon said last named portion, the first named bumper being disposed in a plane in advance of the second named bumper.

6. The combination with a door and a door jamb therefor, of means mounted upon the door jamb for checking the door comprising a link operatively mounted upon the door jamb for movement in a plane parallel to the face thereof, a bumper mounted upon the lower end of the link and projecting in front thereof, a second link swingingly engaged with the first named link and oscillatable with the first named link or independently thereof in the same plane as the first named link or independently oscillatable in a plane at right angles thereto, the second named link carrying a bumper, the bracket supporting said bumpers in front of the face of the jamb and with portions of the bumpers disposed in the path of movement of the door.

In testimony whereof I hereunto affix my signature.

M. E. TATE.
